UNITED STATES PATENT OFFICE.

EDWARD D. CHIPMAN AND EDWARD L. D. FOSTER, OF GOSHEN, INDIANA.

SPRING FOR BEDS, CUSHIONS, &c.

SPECIFICATION forming part of Letters Patent No. 470,472, dated March 8, 1892.

Application filed September 19, 1891. Serial No. 406,213. (No model.)

To all whom it may concern:

Be it known that we, EDWARD D. CHIPMAN and EDWARD L. D. FOSTER, both citizens of the United States, and residents of Goshen, in 5 the county of Elkhart and State of Indiana, have invented certain new and useful Improvements in Combination-Springs for Beds, Cushions, &c.; and we do declare the following to be a full, clear, and exact description 10 of the invention, such as will enable others skilled in the art to which it appertains to make and use the same, reference being had to the accompanying drawings, and to letters of reference marked thereon, which form a 15 part of this specification.

Figure 1 of the drawings is a top plan view. Fig. 2 is an end view, and Fig. 3 is a vertical transverse section.

This invention has relation to springs for 20 beds, cushions, sofas, chair-seats, &c.; and it consists in the novel construction and arrangement thereof, as hereinafter set forth.

In the accompanying drawings, illustrating the invention, the letter A designates the 25 frame, which may be rectangular or of any other desired shape, to each side piece of which is secured a series of springs B. These springs consists each of a wire secured at each end to the side piece a short distance from each 30 other. The end portions are then each formed into a coil b, the intermediate portion being extended upwardly to form the loop C. The coils b b of the springs all lie in the same line and have passed therethrough a longitudinal 35 rod D, serving to stiffen the springs and to give them a uniform connected action. The coils b b are so formed that when the loops C are depressed their tension will be increased.

F F represent a series of transversely-extending coil-springs, connected at each end 40 to the rods d, one for each end of the springs B. These springs F F consist each of a sin-

gle spiral coil and are arranged in arc form, having their greatest elevation at the transverse center. Near each end each spring F 45 has one of its coils intersected by the forward end of the loop C. Instead of the coil-spring a band or other suitable spring may be employed and connected to the springs B, so as to give them a combined action.

By varying the shape and size of the frame it is evident that the springs may be employed for use in all kinds of upholstering, or where a spring-cushion of seat is desired, as well as 50 in beds.

Having described our invention, what we claim as new, and desire to secure by Letters Patent, is—

1. The combination, with the frame having at each side a series of springs secured thereto, each spring having a coil near each end and its intermediate portion formed into a loop, and the bar or rod passed through said coils, of the springs connected at each end to one of said rods and one of said loops, substantially as specified.

2. The combination, with the frame having the series of springs at each side secured thereto, said springs having each end coils and an intermediate looped portion, and longitudinal 60 rods passed through the coils in each series, of the transverse springs connected at each end to one of said rods, each said transverse spring having one of its coils near each end intersected by the looped portion of one of 65 said side springs, substantially as specified.

In testimony whereof we affix our signatures in presence of two witnesses.

EDWD. D. CHIPMAN.
EDWD. L. D. FOSTER.
